CLAIM

I claim the ornamental design for a gel filled neck pad, as shown and described.

DESCRIPTION

FIG. 1 is a front, top and side perspective view of the gel filled neck pad embodying the design of the present invention.

FIG. 2 is a front elevational view thereof.

FIG. 3 is a rear elevational view thereof.

FIG. 4 is a side elevational view thereof; and,
FIG. 5 is a bottom plan view thereof, the bottom plan view
being a mirror image.
